Attorney,

UNITED STATES PATENT OFFICE.

DAVID L. RAND, OF AYR, NORTH DAKOTA.

MAGNETIC SEPARATOR.

1,138,889.

Specification of Letters Patent.

Patented May 11, 1915.

Application filed January 16, 1915. Serial No. 2,653.

To all whom it may concern:

Be it known that I, DAVID L. RAND, a citizen of the United States, residing at Ayr, in the county of Cass and State of North Dakota, have invented a new and useful Improvement in Magnetic Separators, of which the following is a specification.

This invention relates to a feed regulator adapted especially for use in connection with grain mills, and the object of the invention is to regulate the flow of feed to a series of magnets whereby any iron articles which may have gotten into the grain are caught and prevented from passing to the mill.

I am aware of the fact that regulators have been employed in connection with mills for the purpose of regulating the flow of grain to the mill itself.

This invention is designed more especially to cause the grain to pass the magnets in a comparatively wide and shallow stream and to regulate the flow of such stream, after which the grain is again returned to the feed spout leading to the mill.

In the accompanying drawing: Figure 1 is a perspective view of the device. Fig. 2 is a detail sectional view illustrating the manner of mounting a feed regulating gate.

In the drawings 1 represents a vertically arranged pipe which may be either a part of the regular grain delivery spout, or may be an independent section connected to said spout. The grain delivery spout is continued as indicated at 2, the said spout when my device is applied being interrupted, and the lower portion being off-set with respect to the upper portion, my device being interposed between the sections 1 and 2. The pipe section 1 carries at its lower end a grain chute 3, and is provided with openings 4 in its sides, only one of which is shown in the drawing, the bottom of the section 1 being closed by the chute 3. In addition to the usual side and rear end walls the chute is provided with a transverse partition 5 which terminates short of the bottom of the chute 3 so that grain escaping through the openings 4 can flow under said partition and down the forwardly inclined portion of the chute. This partition prevents the weight of the grain which may accumulate in the upper rear portion of the chute from bearing upon a vertically movable gate 6 which is mounted adjacent to said partition. This gate is connected to a bar 7 which is provided with vertically arranged U-shaped

end portions 8, said U-shaped portions straddling the sides of a chute 3, and their outer members being pivotally connected to bars 9, respectively, which in turn are pivotally connected to the rear of said members to the chute. The forward ends of the bars 9 are supported by suitable springs 10 which in turn are hung from suitable brackets 11. Also hung from the springs 10 is a hopper 12 which carries the pipe 2, and which in turn forms a movable part of the continued grain spout. The mill may be arranged directly below the pipe 2, or this pipe may be a short section telescoping in the regular grain pipe, depending upon the location of the mill and the various pipes. Across the front of the chute 3 is a board 13 having thereupon a series of magnets 14.

As the grain passes down the chute 3 it spreads out into a comparatively wide and shallow stream, and any iron particles contained therein will be caught by the magnets. From the chute 3 the grain falls into the hopper 12 and should the feed become too rapid the weight of grain falling into said hopper will stretch the springs 10 thereby slightly lowering the hopper, and this in turn will draw down the bars 9 and lower the gate 6, thereby reducing the rate of feed. It will be seen therefore that the supply of grain to the magnets is automatically regulated.

What I claim is:—

1. A feed governor adapted to be inserted in an interrupted grain spout, comprising a chute carried by one section of the spout, and a vertically movable hopper coöperating with the other section of the spout, a series of magnets extending transversely across the chute, a vertically movable gate to the rear of said magnets, and means connecting said movable hopper and said gate.

2. A feed regulator comprising a chute, a grain delivery spout having an upper section leading to said chute, a vertically movable hopper carrying a continuation of said grain spout, said continuation being off-set with respect to the upper section, a series of magnets arranged transversely across the lower end of the chute and above said hopper, a gate, U-shaped members carried by the gate and straddling the sides of the chute, pivoted bars to which said members are pivotally connected, and common means for supporting the forward ends of the bars and the hopper.

3. A device of the kind described comprising a chute, a grain delivery spout adapted to discharge into the upper rear portion of the chute, a transverse partition in advance 5 of said spout, said partition terminating short of the bottom of the chute, said chute being comparatively wide with respect to the diameter of the spout, a vertically movable gate arranged in advance of said 10 partition, a series of magnets arranged in advance of said gate, pivoted bars,

means connecting the gate to the bars, a hopper, coil springs secured at their upper ends to a fixed support having their lower ends connected to said hopper, the front ends 15 of said bars being also connected to said springs.

DAVID L. RAND.
